STAND FOR SPOOLS

Henry Joseph Isabelle, Sr., Fitchburg, Mass., assignor of one-half to Jerry Asher, Fitchburg, Mass.

Application August 19, 1947, Serial No. 769,495

5 Claims. (Cl. 112—218)

1

This invention relates to stands for supporting spools of thread. It has been proposed to provide various types of stands in which all of the spools are supported substantially in a vertical plane in front of the operator. Such stands known as racks have a limited capacity because only a few large spools may be accommodated on the rack, or the rack may be so constructed that a number of small spools, such as are commonly employed in a home, may be mounted on the rack directly in front of the operator.

It is an object of the present invention to provide a stand for accommodating a plurality of large spools, said stand being substantially L-shaped and secured to one corner of a sewing table and to the right of the operator so that the operator will have convenient access to all of the spools without it being necessary for the operator to rise.

Another object of the invention is the provision of a simple and efficient stand for large spools of thread in which spindles for receiving the spools in an upright manner are mounted on an L-shaped top plate carried by a bracket or base formed of an L-shaped metal sheet that has flanges at the upper edge secured to the under face of the plate and flanges at the bottom edges secured to a corner of a table top, said bracket at the intermediate angular portion having a large opening to permit the entrance of light to the sewing machine.

A further object of the invention is the provision of a stand for accommodating a number of spools in a convenient position for the operator so that it will be unnecessary for said operator to rise when changing the threads, said stand being L-shaped so that a number of the spools are partly in front of the operator while the remaining spools on spindles are disposed slightly to the right in embracing relation with the sewing machine, said stand having a large opening therein for supplying light to the sewing head of the machine.

The invention consists in the novel constructions, arrangements and combinations of parts hereinafter more particularly described and claimed.

In the drawings:

Figure 1 is a plan view of my stand.

Figure 2 is a front end view in elevation of the stand, and

Figure 3 is a rear view in perspective of the stand.

Referring more particularly to the drawings, 10 designates a bracket or base member which is

2

substantially L-shaped in plan. The bracket is made of a single sheet of metal which is bent intermediate its ends along a curve. The intermediate curved portion is cut away, as shown at 11, and said cut-a-way portion extends at opposite sides of the central portion, side walls 12 and 13 of the bracket. The cut-away portion provides a large window for the transmission of light rays to the sewing head of the machine for the benefit of 10 the operator.

Flanges 15 extending inwardly from the bottom edges of the walls 12 and 13 are provided with passages 16 for receiving screws to attach the bracket 10 to one corner of a top 17 of a sewing table (Fig. 3). The upper edges of the walls have outturned flanges 18, 19 and 20. The flange 18 projects from the wall 12 while the flange 19 projects from the wall 13. The plurality of flanges 20 are formed integrally with the curved intermediate portion of the bracket.

An L-shaped top plate 21 which forms the support for spindles 22 has its under face welded or riveted to the top faces of the flanges 18, 19 and 20. Vertical planes passing through the walls 12 and 13 cut the plate 21 inwardly of lines running midway of the opposite edges of the plate. It will be noted from Figures 2 and 3 that the ends 30 of the plate are round and extend beyond the outer vertical edges of the walls 12 and 13.

30 Spaced spindles 25 are secured within the passages in the top plate 21. The lower end of each spindle is threaded to receive a nut 26. This nut is seated upon the plate while a nut 27 below said plate secures the spindle in place. The spindles 35 are arranged along the plate with the end spindles being carried by the projecting ends 30 of the plate.

Means is provided for guiding the working thread to the needle of the machine and for 40 retaining the idle threads within easy reach of the operator so that it will not be necessary for the operator to rise when changing the thread. The means includes vertical rods 31 which have the lower ends thereof secured to the plate 21 by pairs of nuts 32 and 33. This manner of attachment for the rods 31 is identical with the means for securing the spindles 22 to the plate. The rods are connected to the plate outwardly of the spindles and at points on said plate where 45 they will not interfere with the rotation of spools of thread 34. The upper ends of the rods have inturned ends 35 to which is welded an L-shaped bar 36. It will be noted that there are three vertical rods, one at each end of the plate and one at the curved or angular portion of said

plate. An eye 40 is located above each spindle and is attached to the bar 36. These eyes are split to provide a passage for the reception of the thread so that it will not be necessary to thread the eye since the thread may be laid over the passage and dropped directly into the eye. The eyes will support various threads in positions so that they may be grasped readily by the operator but also in a manner that they will not become entangled due to the fact that the 10 spindles are spaced sufficiently apart and the bar 36 carrying the eyes is located in a plane which is outwardly of the spindles.

A supplementary bar 41 projects inwardly from the curved or angular portion of the bracket 13 as shown in Figures 1 and 2. This spindle is secured to said angular portion in the same manner as are the rods 31 attached to the plate 21. An eye 42 is secured to the end of the bar and receives the thread from one of the eyes 40 before it is directed to the sewing head of the machine.

I claim:

1. A stand for spools comprising a vertically disposed base member formed of a single sheet of metal, said sheet being bent intermediate the ends thereof at substantially a right angle, a section of the angular portion of the base member being cut away to provide a window, inturned flanges at the bottom edge of the base member at opposite sides of the window adapted to be secured to the corner of a sewing table, outturned flanges at the top edge of the base member, a top plate L-shaped in plan secured to the top flanges of the base members, vertically disposed spindles mounted on the top plate, and means on the top plate for guiding the thread.

2. A stand for spools comprising a vertically disposed base member formed of a single sheet of metal, said sheet being bent intermediate the ends thereof at substantially a right angle, a section of the angular portion of the base member being cut away to provide a window, inturned flanges at the bottom edge of the base member at opposite sides of the window adapted to be secured to the corner of a sewing table, outturned flanges at the top edge of the base member, a top plate L-shaped in plan secured to the top flanges of the base members, vertically disposed spindles mounted on the top plate, and means on the top plate for guiding the thread, the ends of the top plate projecting beyond the end edges of the base member and carrying a spindle.

3. A stand for spools adapted to be secured to

the table top at one corner of a sewing machine table comprising a vertically disposed base bent intermediate the end edges thereof to form an L-shaped member, flanges at the bottom of the base secured to the table top, flanges at the top edges of the base, said base being provided with a window for the transmission of light to the sewing head of the machine, an L-shaped and horizontally disposed top plate secured to the top flanges and spaced vertical spindles mounted on the top plate.

4. A stand for spools adapted to be secured to the table top at one corner of a sewing machine table comprising a vertically disposed base bent intermediate the end edges thereof to form an L-shaped member, flanges at the bottom of the base secured to the table top, flanges at the top edge of the base, said base being provided with a window for the transmission of light to the sewing head of the machine, an L-shaped and horizontally disposed top plate secured to the top flanges, spaced vertical spindles mounted on the top plate, and means rising from the top plate and provided with eyes for guiding the thread wound on spools carried by the spindles, said means supporting the eyes in vertical planes located outwardly of vertical planes passing through the vertical axes of the spindles.

5. A stand for spools adapted to be secured to the table top at one corner of a sewing machine table comprising a vertically disposed base bent intermediate the end edges thereof to form an L-shaped member, flanges at the bottom of the base secured to the table top, flanges at the top edge of the base, the bent portion of the base being curved, said base being provided with a window formed by a cut-away portion of the bent portion thereof, the cut-away portion extending into the sections of the base at each side of the curved portion, an L-shaped and horizontally disposed top plate secured to the top flanges on the base and spaced vertical spindles mounted on the top plate.
